FASTENER APPLYING DEVICE

Herman J. Spencer, Ingomar, Pa.

Application March 20, 1953, Serial No. 343,591

2 Claims. (Cl. 1—49)

1

This invention relates to improvement in stapling machines wherein a driver is actuated to drive a staple from an arm containing staples and spring means is usually employed to urge the staple-carrying arm or a clincher arm towards the opposite arm to grip material to be stapled, the spring in some cases being compressed as the driver is actuated.

One object of the invention is to provide means whereby pressure applied on a single lever is transmitted in part to the driver to actuate the latter and the balance of the pressure so applied is rigidly transmitted to one of the arms to urge the latter towards the opposite arm for gripping material between the arms as the applied power urges the driver to secure a staple in said material.

In the accompanying drawings which illustrate a present preferred embodiment of my invention—

Figure 1 is a sectional view in side elevation showing a plier type stapling machine embodying one arrangement of the operating lever used to actuate the driver and simultaneously urge the staple-carrying arm towards the staple clincher arm for gripping material therebetween.

Figure 2 is a view in side elevation showing the device in Figure 1 with the arms as having been moved towards each other and the driver as having been moved in fastener applying direction.

Figure 3 is a cross-section of Figure 1 at 3—3.

Referring to the drawings, the stapling machine comprises a magazine arm 1 which is of the usual type, containing an ejection chute 10 at its one end, a reciprocably mounted driver 3 for ejecting the staple S, a staple pusher 11, a feeder spring 12 adapted to urge the pusher 11 to feed the staples S along the staple guide 27 towards the ejection chute 10 and a feeder spring guide rod 13 for holding the feeder spring 12 in proper alignment. As shown in Figure 1, a block 14 is secured to the pusher 11 and feeder spring 12 is urging the pusher block 14 towards the ejection chute 10.

Note in Figures 1 and 3 that the inverted U-shaped bracket 16 is secured to the underside of the magazine arm 1 and has its flanges 28 pierced to receive shafts 5 and 7. An anvil arm 2 contains staple clinching means 4 on its one end and arm 2 is pivoted in relation to the magazine arm 1 on shaft 5 to permit said arms' one ends to move towards each other to grip material to be stapled. See Figure 2. A staple driving arm 6 is pivoted on the magazine arm 1 by shaft 7, the latter being located at a point away from shaft 5 and

2

thereby a part of pressure applied to the staple driving arm 6 is transmitted to the magazine arm 1 through shaft 7 to urge shaft 7 to move in an arc counter-clockwise around shaft 5 to thereby urge the ejection chute end 10 of the magazine arm 1 towards the clincher means 4 of the anvil arm 2. See Figures 1 and 2. The staple driving arm 6 has upwardly extending sides 8 which are formed inwardly at 9 for entering opening 24 in the driver 3 and arm 6 is adapted thereby to transmit the balance of pressure applied to it to the driver 3 to reciprocate the latter. See Figures 1 and 2. As shown, the sides 8 of the staple driving arm 6 have an integral web portion 23 which forms the balance of the hand-grip and the latter underlies the magazine arm 1.

As shown in the accompanying drawings, the anvil arm 2 has side portions 21 extending upward on both sides of the device and are integral with a web portion 22 which extends longitudinally and overlies the magazine arm to form a part of a hand-grip opposite from the hand-grip portion of the staple driving arm 6.

Notice in Figure 1 that the inward portion 9 of the staple driving arm 6 is against stop 25 of the anvil arm 1 to limit upward movement of the driver 3 relative to the magazine arm 1 and that lugs 26 on the staple driving arm 6 are in contact with the forward edges 15 of the side portions 21 of the anvil arm 2 to limit the counter-clockwise rotation of the latter on shaft 5.

A spring 17 has its coils resting against the underside of bracket 16 at a point between the central portions of shafts 5 and 7. Spring 17 has one leg 18 resting on the inside of the hand-grip portion or web 23 of the staple driving arm 6 for rotating the latter clockwise on shaft 7 to thereby raise the driver 3 in relation to the magazine arm 1 and spring 17 has its other leg 19 exerting pressure on pin 20 which is supported on the anvil arm 2 for rotating the latter counter-clockwise on shaft 5 for moving the clincher end 4 of the anvil arm 2 away from the ejection chute end 10 of the magazine arm 1.

In Figure 1 the device is shown with the anvil and magazine arms spaced apart to receive material, the driver 3 is in a raised position in the magazine arm 1 to permit a staple S to be moved into the ejection chute 10 by the pusher 11 under the influence of feeder spring 12 and under these conditions, the device operates as follows: the device is held in one hand and manual pressure is applied to the hand-grip portions 23 and 22 of the staple driving arm 6 and of the anvil arm 2 respectively; as pressure is applied as mentioned

above, the coiled portion of spring 17 is pressing against the underside of magazine arm 1 and spring 17 has a leg 18 restraining the staple driving arm 6 from pivoting counter-clockwise on shaft 7 and thereby in relation to the magazine arm 1. The other leg 19 of spring 17 as previously explained is restraining clockwise movement of the anvil arm 2 on shaft 5 and is thereby restraining the clincher end 4 of the anvil arm 2 from moving towards the ejection chute end 10 of the magazine arm 1. See Figure 1.

A study of Figures 1 and 2 will show that it is unimportant at the beginning of a fastening operation as to whether the anvil arm 2 pivots on shaft 5 to move its clincher end 4 towards the ejection chute end 10 of the magazine arm 1 or should the anvil arm 2 remain stationary while the magazine arm 1 is pivoted counter-clockwise on shaft 5 by the dual pressure by the coils of spring 17 against bracket 16 which is secured to the magazine arm 1 and by the pressure transmitted from the staple driving arm 6 through shaft 7 to the magazine arm 1 to move the latter's ejection chute end 10 towards the clincher end 4 of the anvil arm 2 with shaft 7 thereby moving with the magazine arm 1 in an arc counter-clockwise around shaft 5. See Figures 1 and 2.

Therefore, in view of the above explanation, as pressure is applied to the device at the beginning of a fastening operation, said dual pressure urges the magazine arm 1 to pivot counterclockwise on shaft 5 to thereby move the ejection chute end 10 of the magazine arm 1 towards the clincher end 4 of the anvil arm 2 until such relative movement between arms 1 and 2 is stopped by contact with material placed between the latter arms. When the anvil arm 2 and the magazine arm 1 are stopped, as described, and further pressure is applied on the device, the staple driving arm 6 will pivot counter-clockwise on shaft 7 against the resistance of leg 18 of spring 17 to thereby transmit part of the pressure applied on the driving arm 6 to the driver 3 to move the latter towards the clincher end 4 of the anvil arm 2 to thereby eject a staple 5 from the magazine arm 1 into the material being gripped and the balance of the pressure being applied to the driving arm 6 is being transmitted through shaft 7 to the magazine arm 1 to rigidly urge the ejection chute end 10 of the magazine arm 1 to grip one side of the material during the fastener applying operation.

I claim:

1. In a stapling machine, comprising a magazine arm and an anvil arm, said arms pivoted

10
15

in relation to each other, said magazine arm having adjacent its one end a material gripping portion and a staple ejection chute, said anvil arm having a portion adjacent its one end adapted to give the opposite side of material and having means for clinching a staple, means carried by said magazine arm for feeding staples to said ejection chute, a staple ejecting driver, means mounting said driver for reciprocating movement in the one end of said magazine arm: hand-grip means on one of said arms for urging its one end to grip one side of material, a staple driving arm provided with hand-grip means, said staple driving arm operably connected to rigidly reciprocate said driver, operable connector means between said staple driving arm and the other of said arms adapted to rigidly transmit a part of the pressure applied on said staple driving arm to said other arm to urge the latter to grip the opposite side of material while the balance of said applied pressure is rigidly transmitted to said driver to urge the latter to secure a staple in said material.

2. In a stapling machine, comprising a magazine arm and an anvil arm, said arms pivoted in relation to each other, said magazine arm having adjacent its one end a material gripping portion and a staple ejection chute, said anvil arm having a portion adjacent its one end adapted to grip the opposite side of material and having means for clinching a staple, means carried by said magazine arm for feeding staples to said ejection chute, a staple ejecting driver, means mounting said driver for reciprocating movement in the one end of said magazine arm: means for holding said anvil arm against one side of the material to be stapled, a staple driving arm, operable connector means connecting said driver and said magazine to said staple driving arm adapted to rigidly transmit a part of pressure applied on said staple driving arm to said magazine arm to urge the latter to grip the opposite side of the material while the balance of said applied pressure is rigidly transmitted to said driver to urge the latter to secure a staple in said material.
